UNITED STATES PATENT OFFICE.

JAMES A. CLARKE, OF YONKERS, NEW YORK, ASSIGNOR TO CALKINS & HOLDEN, OF NEW YORK, N. Y., A CORPORATION OF NEW YORK.

POWDER BOX.

Application filed November 5, 1927. Serial No. 231,274.

This invention relates to improvements in powder boxes used in preparing the toilet, and the primary object of the invention is to provide a device of this kind wherein simple and efficient means is provided for enabling one to readily cause a powder puff or applicator to take up or receive small quantities of the powder for application purposes, without danger of spilling the powder or taking up an excessive quantity thereof.

A further object is to provide a powder box of the above kind embodying a main box or container and a refill powder containing element removably fitted in the main box or container so as to be capable of ready replacement by a new refill element from time to time as found necessary.

A still further object is to provide a powder box characterized as above and embracing a simple and durable construction capable of being manufactured cheaply and readily.

Other objects will appear as the nature of the invention is better understood, and the same consists in the novel form, combination and arrangement of parts hereinafter more fully described, shown in the accompanying drawing and claimed.

In the drawing, wherein like reference characters indicate corresponding parts throughout the several views,

Figure 1 is a perspective view of a powder box embodying the present invention;

Figure 2 is a transverse section thereof taken on line 2—2 of Figure 1;

Figure 3 is a view similar to Figure 2 with the cover of the main box removed and the powder puff or applicator depressed as in the act of taking up the powder from the refill element;

Figure 4 is a horizontal section on line 4—4 of Figure 3; and

Figure 5 is a top plan view of the refill element with the bottom section of the main box indicated by dotted lines in operative relation thereto.

Referring more in detail to the drawing, the present powder box includes a main box or container composed of a lower section having a hollow open top body 5, and a slip-on cover 6 adapted to snugly fit over the body 5. The top wall of the cover 6 may be provided with a suitable raised ornamentation 7 having a central depression as at 8 within which a suitable trade-name may be

affixed by means of a sticker, printing or the like.

The cavity of the body 5 of the main box may be of any desired configuration, but is shown as hexagonal, and arranged to snugly and removably fit within said cavity is a similarly shaped refill powder container 8. The powder container or refill element 8 is composed preferably of a body and top wall of relatively stiff cardboard or the like while the bottom thereof is preferably closed by means of a paper wall 9 having its margin upturned around the body of the container 8 as at 10 and secured thereto by adhesive or the like. In this way the powder may be placed within the body of the container 8 while the latter is inverted and then the closure sheet or wall 9 may be applied.

The top wall 11 of the powder container 8 is of funnel-shape extending downwardly and inwardly from the upper edge of the body of the container 8 to a point adjacent but in slightly spaced relation to the bottom wall 9 centrally of the latter, where it is provided with a central relatively large opening as at 12.

It will thus be seen that the bulk of the powder is normally retained in the body of the container 8 in surrounding relation to the opening 12, and when the usual powder puff or applicator 13 is pressed downwardly through the opening 12 into contact with the bottom wall 9 of the refill powder container, such powder as is disposed in a thin layer upon the bottom wall 9 within the area of the opening 12 will be taken up by the powder puff. It will also be seen that when the puff is elevated a slight suction will be created to again draw a quantity of the powder inwardly to the central portion of the bottom 9 within the area of the opening 12, whereby when the powder puff is again inserted a quantity of powder will be in position for being taken up. In this way no difficulty will be found in taking up the powder in small quantities, although taking up of excessive quantities of the powder or spilling of the same will be effectively prevented. Naturally, by reason of the funnel-shaped form of the top wall 11, the latter will furnish a cavity or recess for receiving the powder puff when not in use as shown in Figure 2.

As the refill powder container 8 is readily removable from the cavity of the body 5 of the main box, new refill elements may be in-

serted to replace the used ones as found necessary from time to time. Thus, I have provided a practical means whereby a refill element may be employed handling the powder in loose form instead of cake form as heretofore practiced with refill elements.

Minor changes may be made without departing from the spirit and scope of the invention as claimed.

10. What I claim as new is:

A powder box comprising a main box body having a removable cover, and a refill ele-

ment removably fitted in said body, said refill element including a hollow body having a centrally apertured downwardly and inwardly tapering top wall extending to a point above and in close proximity to the central portion of the bottom of said hollow body, the hollow body and its top wall being relatively stiff, and a paper closure 15 for the bottom of said hollow body.

20 In testimony whereof I affix my signature.

JAMES A. CLARKE.
